United States Patent Office.

JOHN H. BELLAMY, OF CHARLESTOWN, MASSACHUSETTS, ASSIGNOR TO HIMSELF AND D. A. TITCOMB, OF THE SAME PLACE.

Design No. 2,778, dated September 10, 1867.

DESIGN FOR A CLOCK-CASE.

The Schedule referred to in these Letters Patent and making part of the same.

TO WHOM IT MAY CONCERN:

Be it known that I, JOHN H. BELLAMY, of Charlestown, in the county of Middlesex, and State of Massachusetts, have invented a new and improved Design for a Clock-Front; and I hereby declare that the following is a full and exact description thereof, reference being had to the accompanying photograph.

My invention consists of a clock-front, so constructed and arranged as to produce an open-work emblematic design. In the accompanying photograph—

A represents a circular opening in the clock-front, intended for the insertion of the dial of the clock. Above the dial opening, and resting upon its circle, are a square, B, and a pair of compasses, C, enclosing a double cross, D. Above, and resting upon the pair of compasses, is a Christian cross, E, with rays, while above the Christian cross is an arch or semicircle, F, inscribed "*In hoc signo vinces.*" Below the circle A are two swords crossed, G, and below the swords is an opening, H, for showing and starting the pendulum of the clock. On the left of the opening H is the representation of a seal, with a Christian cross, I; on the right is a Maltese cross, J, the whole being supported by ornamental scroll-work.

What I claim, and desire to secure by Letters Patent, is—

The design for a clock-front, substantially as shown and described.

JOHN H. BELLAMY.
